(57) CLAIM

The ornamental design for a sandal holder, as shown and described.

DESCRIPTION

FIG. 1 is a side view of a sandal holder showing our new design;

FIG. 2 is a side view thereof, shown with cross sectional dissections for ease of illustration;

FIG. 3 is a cross sectional view taken along line 3—3 of FIG. 2;

FIG. 4 is a cross sectional view taken along line 4—4 of FIG. 2;

FIG. 5 is a cross sectional view taken along line 5—5 of FIG. 2; and,

FIG. 6 is a cross sectional view taken along line 6—6 of FIG. 2.

All sides not shown form no part of the claimed design.
